(57) **CLAIM**

The ornamental design for a kiosk, as shown and described.

DESCRIPTION

FIG. 1 is a top, front, and right side perspective of a first embodiment of a kiosk embodying my new design.

FIG. 2 is a top, back, and right side perspective of the embodiment of FIG. 1.

FIG. 3 is a front view of the embodiment of FIG. 1.

FIG. 4 is a back view of the embodiment of FIG. 1.

FIG. 5 is a right side view of the embodiment of FIG. 1.

FIG. 6 is a left side view of the embodiment of FIG. 1.

FIG. 7 is a top view of the embodiment of FIG. 1.

FIG. 8 is a bottom view of the embodiment of FIG. 1.

FIG. 9 is a top, front, and right side perspective of a second embodiment of a kiosk embodying my new design.

FIG. 10 is a top, back, and right side perspective of the embodiment of FIG. 9.

FIG. 11 is a front view of the embodiment of FIG. 9.

FIG. 12 is a back view of the embodiment of FIG. 9.

FIG. 13 is a right side view of the embodiment of FIG. 9.

FIG. 14 is a left side view of the embodiment of FIG. 9.

FIG. 15 is a top view of the embodiment of FIG. 9.

FIG. 16 is a bottom view of the embodiment of FIG. 9.

FIG. 17 is a top, front, and right side perspective of a third embodiment of a kiosk embodying my new design.

FIG. 18 is a top, back, and right side perspective of the embodiment of FIG. 17.

FIG. 19 is a front view of the embodiment of FIG. 17.

FIG. 20 is a back view of the embodiment of FIG. 17.

FIG. 21 is a right side view of the embodiment of FIG. 17.

FIG. 22 is a left side view of the embodiment of FIG. 17.

FIG. 23 is a top view of the embodiment of FIG. 17; and,

FIG. 24 is a bottom view of the embodiment of FIG. 17.

The portions of the Figures shown in broken lines disclose environmental structure and form no part of the claimed design.

1 Claim, 21 Drawing Sheets
